UNITED STATES PATENT OFFICE.

CARL NELSON, CARL ALBERT NELSON, AND HARRY T. NELSON, OF BROOTEN, MINNESOTA.

ADJUSTABLE STOVEPIPE.

No. 797,069.

Specification of Letters Patent.

Patented Aug. 15, 1905.

Application filed March 20, 1905. Serial No. 251,173.

To all whom it may concern:

Be it known that we, CARL NELSON, CARL ALBERT NELSON, and HARRY T. NELSON, citizens of the United States, residing at Brooten, in the county of Stearns and State of Minnesota, have invented a new and useful Adjustable Stovepipe, of which the following is a specification.

This invention relates to improvements in stovepipes capable of adjustment longitudinally, and has for its object to produce a simply-constructed and efficient device of this character whereby the several sections of stovepipe may be adjusted to any required extent and securely locked in the adjusted position.

With these and other objects in view, which will appear as the nature of the invention is better understood, the same consists in certain novel features of construction, as hereinafter fully described and claimed.

In the accompanying drawings, forming a part of this specification, and in which corresponding parts are denoted by like designating characters, is illustrated the preferred form of embodiment of the invention capable of carrying the same into practical operation, it being understood that the invention is not necessarily limited thereto, as various changes in the shape, proportions, and general assemblage of the parts may be resorted to without departing from the principle of the invention or sacrificing any of its advantages.

In the drawings thus employed, Figure 1 is a perspective view of portions of two sections or lengths of pipe embodying the improvements. Fig. 2 is a transverse section of the seam shown in Fig. 1, with the outer pipe-section in plan view. Fig. 3 is an enlarged detail of a portion of the outer pipe-section of the form illustrated in Fig. 1. Fig. 4 is a side view of portions of two pipe-sections, illustrating a modification in the construction of the improved seam. Fig. 5 is a transverse section on the line 5 5 of Fig. 4. Fig. 6 is a side view of a portion of a pipe-section, illustrating another modification in the construction.

The piping-sections 10 and 11 employed in connection with the invention herein described and shown are of the usual form with the ordinary folded seams 12 13, except that the lengths of pipe are uniform in diameter

throughout, so that one will move longitudinally within the other.

Formed in the outer pipe 11 is a tongue 14, which may be formed at one end of the section, as in Figs. 1, 3 and 4, or intermediately thereof, as in Fig. 6, as may be preferred.

Formed transversely of the "fold" portion 12 of the inner pipe-section 10 are recesses 15, into one of which the tongue 14 is adapted to be "entered" as the outer pipe-section is adjusted longitudinally over the inner section, as indicated in Fig. 1. The recesses 15 may be formed entirely through the fold 12, as in Figs. 4 and 5, or through one side only, as in Figs. 1 and 2, as may be preferred.

In operating the device the inner pipe-section is rotated within the outer section or the outer section rotated around the inner section, as the case may be, until the tongue 14 is free from the recess 15 and the piping adjusted to the required extent and the piping rotated back again until the tongue enters the nearest recess. Then the two pipe-sections will be firmly locked in position. Thus the piping may be adjusted longitudinally to any required extent and locked in the adjusted position.

The device is simple in construction, does not weaken the pipe, and does not in any manner affect the operation or materially increase the expense of construction.

By this means the piping may be quickly and easily shortened and without cutting the lengths or otherwise injuring them or decreasing the value.

Having thus described the invention, what is claimed is—

An adjustable stovepipe comprising telescoping pipe-sections each having an ordinary lock-seam, one section having a plurality of transverse spaced recesses within the folds of the seam and the other section having a tongue adapted for engagement with any one of said apertures.

In testimony that we claim the foregoing as our own we have hereto affixed our signatures in the presence of two witnesses.

CARL NELSON.

CARL ALBERT NELSON.

HARRY T. NELSON.
